UNITED STATES PATENT OFFICE.

GEORGE MITCHELL, OF LOS ANGELES, CALIFORNIA.

APPARATUS FOR AERIAL NAVIGATION.

1,074,281.

Specification of Letters Patent. Patented Sept. 30, 1913.

Application filed April 28, 1910. Serial No. 558,180.

To all whom it may concern:

Be it known that I, GEORGE MITCHELL, of Los Angeles, in the county of Los Angeles and State of California, have invented certain new and useful Improvements in Apparatus for Aerial Navigation; and I do hereby declare the following to be a full, clear, and exact description of the invention, such as will enable others skilled in the art 10 to which it appertains to make and use the same.

My invention relates to improvements in apparatus for aerial navigation and more particularly to that class known in the art 15 as aeroplanes.

One object of my present invention is to provide means whereby a machine of the type specified can be caused to rise vertically from the ground, or so that it can be made 20 to rise and simultaneously move forward.

A further object is to construct the machine in such manner as to provide a compartment for the accommodation of the aviator and to locate in this compartment 25 the various devices by means of which the machine can be operated and controlled.

A further object is to locate the weighty devices, such as engines, that in case of accident the machine will descend without 30 danger of turning over.

A further object is to provide the machine with auxiliary propelling devices which can be thrown into operation in case of the breakage of an active propeller.

35 With these objects in view the invention consists in certain novel features of construction and combinations and arrangements of parts as will be hereinafter more fully described and pointed out in the claim.

40 In the accompanying drawings, Figure 1 is a side elevation of an aeroplane of the bi-plane type illustrating my improvements. Fig. 2 is a plan view of the same. Fig. 3 is a front view of same. Fig. 4 is a 45 tail view of shafting and motors, suitable for both horizontal and vertical power plants.

The planes 1 of the machine are supported by suitable framework and at the 50 central portion of and between the planes a framework 2 is located and suitably secured to said planes. The framework 2 projects forwardly from the main planes 1 and at its forward end carries a movable head

elevating plane 3. Laterally movable guiding planes 8^a may be provided in the rear portion of the framework 2. The said frame 2 also projects rearwardly from the main planes and carries a movable tail elevating plane 4. Planes 3 and 4 are connected by 55 steering wires 10 controlling stability when center of gravity is changed. The guiding planes are connected by a cross bar 8^a and wires 8^b are connected with these guiding planes and controlled by a suitable wheel 8^c 60 in the space or compartment 5. Four stabilizing planes 22 and 23 are located on extremities of main planes 1 and connected by an adjusting cord passing over steering wheel located in compartment 5 within 65 reach of operator, same are pivoted to main frame and revolve in the arc shown.

The space or compartment 5 formed by the intersection of the main planes with the frame 2 is intended for the accommodation 75 of the aviator and for the reception of the operating and controlling mechanism of the machine. In the bottom of the compartment 5, a motor or engine 6 is located; connected by a vertical shaft 8 extending upward above 80 said engine and downward below the same,—said shaft being provided at its respective ends with propellers of the screw type as indicated at 11 and 12. Said shaft is suspended by bearings 13 and 14 clamped to 85 members of main frame 2 at points 15 shown in Fig. 4. Instead of a single shaft 8, two telescoping shafts might be employed and each provided at its free end with a propeller. In the front of compartment 5 another engine 7 is suspended from a horizontal shaft 16—said shaft passing through bearings 17 and 18, said bearings clamped to members of main frame 2 at points 15, 90 Fig. 4, and this horizontal shaft imparts 95 motion to propellers 19—20. I prefer to employ the supplemental propellers 12 and 20 which may be conveniently connected with the shafts 8—16 through the medium of suitable clutches 21 which can be operated from 100 within the compartment 5. During the normal operation of the machine the auxiliary propellers may be allowed to remain idle and only brought into action in case one of the active propellers should break, or if desired, both the active and the auxiliary propellers may be operated simultaneously.

Referring to Fig. 4—a bronze collar 25 is

2
shrunken and keyed on shafts 8 and 16 on which revolve roller bearings 26. A bronze bushing, 27, is pressed into bearing casting 17 and 18, being provided with double runway for roller thrust bearing 28.

5 Alighting device consists of wheels 29—frame 30 and springs 31 mounted on rod 32.

By operating one or the other or both of the horizontally disposed propellers 11—12, 10 the machine will be caused to rise vertically from the ground and if desired it can be caused to travel forwardly at the same time by operating one or the other or both of the vertically disposed propellers 19—20. The 15 machine could be operated to cause it to rise and to move forwardly if it were equipped with a single horizontal propeller 11 or 12 and a single vertical propeller 19 or 20.

By locating the engines and the weight of 20 the aviator in the manner above explained, the machine would, in the case of accident be caused to properly descend without danger of turning over.

Having fully described my invention,

what I claim as new and desire to secure by 25 Letters-Patent, is,—

An aeroplane comprising frame-work having a central compartment, propellers above and below and in front and in rear of said compartment, means in said compartment 30 for operating said propellers, main plane sections extending laterally in opposite directions from the upper and lower edges of said compartment, stabilizing planes at the outer ends of the main plane sections, connected head and tail planes, laterally movable guiding planes between said compartment and the tail plane, and means operable from said central compartment for controlling the planes.

35 In testimony whereof, I have signed this specification in the presence of two subscribing witnesses.

40 GEORGE MITCHELL.
